UNITED STATES PATENT OFFICE.

HARRISON H. WELLS, OF DELANCO, NEW JERSEY.

REFRIGERATING APPARATUS.

Application filed April 24, 1924. Serial No. 708,776.

To all whom it may concern:

Be it known that I, HARRISON H. WELLS, a citizen of the United States, residing at Delanco, in the county of Burlington and 60
5 State of New Jersey, have invented certain new and useful Improvements in Refrigerating Apparatus; and I hereby declare that the following is a full, clear, and exact description thereof, reference being had to 10 the accompanying drawings, which form part of this specification.

This invention is a novel improvement in ice boxes, refrigerators, and the like, wherein it is desired to maintain low temperature 15 by the employment of ice.

The primary object of the present invention is to maintain the desired low temperature in the box or refrigerating chamber with less expenditure of ice, by maintaining 20 in the box an amount of the coldest water or brine at all times, and at the same time prevent overflowing of the box; and provide means whereby excess water can be drawn off as desired without disturbing the 25 amount of cold water or brine.

Another object of the invention is to provide novel devices which can be readily attached to a box or refrigerator, whereby, a predetermined depth of cold water or brine 30 30 may always be maintained in the box, and overflowing of the box or refrigerating chamber prevented; and whereby the warmer water above the cold water may be drawn off, as desired, without disturbing the 35 reservoir of cold water or brine.

I will explain the invention with reference to the accompanying drawings which conventionally illustrate one form of ice box equipped with my invention, and an understanding thereof will enable others to adopt and use the same; and summarize in the 40 claims the novel features of the invention and novel combinations of parts for which protection is desired.

45 In said drawings:

Figure 1 is a vertical longitudinal section through a conventional form of ice box, such as is commonly used in packing or storing ice cream or the like, equipped with 50 my invention.

Figure 2 is a vertical section on the line 2—2 Fig. 1, looking in the direction of the arrow.

55 Figure 3 is an enlarged vertical longitudinal section of the attachment, the drain valve being shown open.

Figure 4 is a detail vertical section at right angles to Fig. 1, showing the overflow trap and waste valve, the latter being shown closed. 60

Figure 5 is a transverse section looking downward on the line 5—5, Fig. 4.

The refrigerator or ice box B may be of any desired construction, having a watertight chamber in the refrigerating compartment. In the construction shown, the box 65 has a water-tight chamber A in which are located food receptacles or cans C; but it should be understood that the particular construction of the box, the refrigerating 70 chamber and the food containers are not essential features of the present invention.

Within the refrigerating chamber A and preferably adjacent one end of the box B is an attachment including a drain valve, a 75 water seal trap, and an overflow pipe. The drain valve shown comprises a casting 2 having a central valve chamber 2^a, an internally threaded hollow branch 2^b above the chamber 2^a, an externally threaded hollow branch 2^c below the chamber 2^a; and an internally threaded hollow branch 2^d at another side of the chamber, and preferably located at right angles to the branch 2^b. 80

The branch 2^b is preferably externally 85 threaded for the engagement of the lower end of a cylindrical hollow valve stem guide 3, the lower end of which is internally threaded as at 3^a to engage the external threads of the branch 2^b. A packing ring 90 3^b is preferably placed between the guide 3 and the branch 2^b to form a tight joint. The upper end of the guide 3 is provided with a stuffing box 3^c in which is a packing 95 3^d confined therein by a nut 3^e screwed onto the upper end of the guide.

The valve stem 4^s extends through the guide 3, box 3^c and nut 3^e as shown.

Within the casing 2 is a valve member 4, which is provided with an externally 100 threaded upper end 4^a engaging the internal threads of the branch 2^b. To the lower end of the member 4 is preferably attached a valve disk 4^b, which is adapted, when the valve member is lowered, to seat upon a 105 seat 2^s in the lower part of the chamber 2^a, and surrounding the upper end of the opening in the branch 2^c.

To the member 4^a is connected a stem 4^s, and to the upper end of this stem is connected 110 a handle 4^h of any suitable kind, by which the valve can be operated. The valve

is normally closed, as indicated in Fig. 4; but is shown open in Fig. 3.

The branch 2^a is connected to a drain pipe 5 which may extend through a suitable opening in the box and be secured in place by a nut 5^a. Metal washers 5^a and 5^b may be placed on the pipe 5 inside and outside of the box to make a close water-tight joint therewith. Pipe 5 also forms a means for supporting the attachment in position within the box.

The lower end of the branch 2^c is provided with a screen 6 which may be conveniently retained in position by perforated internally threaded screw cap 6^a, engaging exterior threads on the branch 2^c as shown.

To the branch 2^c is connected the outlet end of a water-seal trap 7; this end of the trap being externally threaded as at 7^a to engage the internal threads of the branch 2^c. The trap 7 is curved, and its outlet end 7^a is normally disposed horizontally but its inlet end 7^b is curved upwardly and lies at right angles to the end 7^a, and the intermediate curved portion of the trap 7 depends below the level of the end 7^a. The trap is provided with an internal partition 7^c, the lower edge of which lies below the level of the lower part of the end 7^a, so that there will be a water seal maintained in the trap as indicated at α in Fig. 4. This seal will prevent any air passing to or from the pipe 5 through the valve chamber from or to the overflow pipe 8 which is connected to the end 7^b of the trap.

The overflow pipe 8 may be of any desired length. It is externally threaded at its lower end to engage the internal threads of the end 7^b of the trap as shown, so as to form a close joint therewith. The upper end 8 of the overflow pipe is provided with a screen 9 which is retained in position thereon by means of a perforated cap 9^a internally threaded to engage external threads on the upper end of the overflow pipe, as shown in Fig. 4.

The pipe 5 is located at such a point along the floor of the refrigerating chamber that the valve 2^s in the casting 2 will be at the level at which it is desired to always maintain an amount of cold water or brine in the box; this level being indicated by the dotted line $y-y$ in Figs. 1 and 2. The overflow pipe 8 is of such length that its upper end will be at the level beyond which it is not desired to have water rise in the box at any time, this level being indicated by the dotted line $z-z$, Figs. 1 and 2.

When the valve is closed, as indicated in Fig. 4, the water level in the box will be maintained at the line $z-z$, Figs. 1 and 2. In such refrigerators the low temperature is commonly provided by a mixture of ice and salt, and the resultant brine is of low temperature, and the coldest brine always

settles to the bottom of the chamber, below the line $y-y$. This brine is as cold or colder than the ice itself, and I have found that it is very advantageous to always retain in the ice box an amount of cold brine, below the level y , and this amount may be from 8 to 12 inches in depth, according to the size of the box. The valve 4 is normally closed, as in Fig. 4, and as the ice melts the water level gradually rises; but will overflow before it overflows the cans.

When it is desired to re-ice the box, the valve is opened, as indicated in Fig. 3, whereupon all water above the level $y-y$ will escape from the chamber through the branch 2^c into the valve chamber 2^a and thence to drain pipe 5. This will withdraw the warmer top water, but the coldest portion of the brine is always maintained in the box below the level y of the valve, and the box can then be refilled with ice. I have found in practice that the retention of a practically constant substantial amount of coldest brine in the chamber effects a very great saving in the amount of ice required to maintain low temperature in the refrigerating chamber; and instead of the whole chamber having to be filled with ice at each icing, only the part of the chamber above the line $y-y$ has to be filled with ice; and the brine below the line y is generally of a temperature as low or lower than that of the ice, obviously no ice is wasted in cooling up the space filled by the brine below the part y .

I claim:

1. In apparatus of the character specified, a refrigerating chamber; means for maintaining a constant amount of brine in the lower portion of said chamber; means to regulate the level of fluid above said constantly maintained amount of brine; means whereby the body of fluid above the constant amount of brine may be drawn off when it is desired to re-ice the apparatus; and means for preventing the passage of air to or from the chamber.

2. In apparatus of the character specified, a refrigerating chamber; a fluid outlet from said chamber located at such point as will retain a constant amount of brine in the chamber; an overflow connected with said chamber to regulate the level of fluid in the box above the constant amount of brine; means whereby the body of fluid above the constant amount of brine may be drawn off when it is desired to re-ice the apparatus; and means for preventing the passage of air through the overflow.

3. In apparatus of the character specified, a box having a refrigerating chamber; means for maintaining a constant amount of brine in the lower portion of said chamber; an overflow pipe extending above the level of the first means to regulate the level of fluid above said constant amount of

brine; a valve whereby the body of water above the constant amount of brine may be drawn off when it is desired to re-ice the apparatus; and means for preventing 5 the passage of air through the overflow pipe.

4. In apparatus of the character specified, a refrigerating chamber; a drain pipe connected with said chamber at such a point above the bottom thereof as will insure the 10 retention of a constant amount of cold brine in the chamber; an outlet valve connected with the drain pipe; an overflow pipe connected with the valve and adapted to regulate the level of the fluid in the box above 15 the constant amount of brine, and means for preventing the passage of air through said overflow pipe.

5. In apparatus of the character specified, a refrigerating chamber; a drain pipe connected with said chamber at such a point as 20 will retain a constant amount of cold brine in the chamber; a valve connected with said pipe; a trap connected with the drain pipe; and an overflow pipe connected with said 25 trap adapted to regulate the level of fluid in the box above the constant amount of brine; said valve permitting the body of water above the constant supply of brine to be drawn off when it is desired to re-ice the 30 box.

6. In apparatus for the purpose specified, a valve casing, a valve therein, a stem for operating said valve; a drain pipe connected with the valve casing; an overflow pipe connected with the valve casing and communicating 35 with the drain pipe through the valve casing; and means for preventing the passage of air through said overflow pipe.

7. In apparatus for the purpose specified, 40 a valve casing, a valve therein, a stem for

operating said valve; a drain pipe connected with the valve casing; a trap also connected with the valve casing and communicating with the drain pipe through the valve casing; and an overflow pipe connected with 45 the said trap.

8. In an apparatus of the character specified, a valve casing having a valve chamber; a valve seat in the lower part of the chamber; an inlet below the seat; a hollow branch above the seat; said casing having another branch adapted to be connected with a drain pipe, and having a second inlet opening in said chamber above the valve seat; a valve member having a threaded portion engaging 50 the hollow branch and adapted to close the seat when the member is lowered; a water seal trap connected with the second inlet opening in the valve casing; and an overflow pipe connected with the trap. 55

9. In apparatus of the character specified, a valve casing having a valve chamber; a valve seat in the lower part of the chamber, a branch below the seat having an inlet opening; a second branch above the seat, a third branch adapted to be connected with a drain pipe, and a fourth branch opening into said chamber above the valve seat; a valve member having a threaded portion engaging 60 the second branch and adapted to 65 close the seat when the member is lowered; a water seal trap having one end connected with the fourth branch; an overflow pipe connected with the other end of said trap; a valve guide connected with the casing; and a valve stem connected with said member and extending through said guide. 70

In testimony that I claim the foregoing as my own, I affix my signature.

HARRISON H. WELLS.
